FRED EVANS, OF SUMMIT, NEW JERSEY, ASSIGNOR, BY MESNE ASSIGNMENTS, TO
VOICES INCORPORATED, A CORPORATION OF DELAWARE.

TALKING-TOY MECHANISM.

Application filed March 21, 1923. Serial No. 626,502.

This invention relates to sound-producing devices such as are used in connection with talking toys, more particularly talking dolls. Specifically, this device is intended 5 and designed for use in connection with a doll, the position of which may be changed, this movement causing the doll to emit a sound such as "ma-ma".

One of the objects of this invention is to 10 produce a simple, effective and inexpensive sound producing mechanism by means of which the human voice may be simulated, the device being so proportioned that it may be concealed within the body of such a doll 15 and operable by changes in position of the body of the doll to produce sounds.

Further and more specific objects, features and advantages will more clearly appear from the detail description given below taken in connection with the accompanying drawings which form a part of this specification.

In the accompanying drawings, wherein I have shown a preferred form of embodiment of my invention:

Figure 1 is a view of the device in side elevation, parts being shown in cross-section.

Figure 2 is a view in perspective of the sound controlling elements.

Figure 3 is a detail cross-sectional view showing the mounting of the reed.

With reference now to the drawings in which similar reference characters refer to 35 similar parts throughout the several views thereof, reference character 1 designates a casing serving to enclose and protect the working parts of the device and preferably constructed of card-board, fibre, or other 40 like material of that character.

Positioned within the casing is a head 2 situated intermediate the ends of the casing and channelled along one face as indicated at 3. Attached to the channelled face of 45 the head is a bellows 4, here shown to be tubular in form and having one marginal edge attached to the head and held in place in the channel by a spring ring 5. The other end of the bellows is closed by a disc 6, 50 preferably made of a heavy material such as lead. Attached to the disc 6 and extending through the bellows and through an aperture in the head 2 is an operating rod 7. It will be noted that the bellows 4 has suit-

able creases as indicated at 8 so that it may 55 be readily collapsed so as to expel the air therefrom.

Positioned on the other face of the head 2 are the sound producing and regulating parts. The head 2 has drilled therethrough an aperture 9 and positioned on the exterior face of the head so as to enclose this aperture is a reed chamber 10, in which is mounted a reed 11, extending through the wall of the reed chamber and into a sound controlling chamber 12 in which is situated an orifice 13. The reed 11 is so disposed that upon expulsion of the air from the bellows the air will cause the reed to vibrate and produce a sound. It will be seen that 70 the orifice chamber has mounted on its outer face various devices by means of which the orifice 13 may be opened and closed, these closure devices being positioned so as to be operated by the rod 7, one end of which is 75 bent laterally as at 7^a so as to engage the closure members.

Overlying the orifice 13 is a swinging door 14 hinged to the edge of the orifice chamber by any suitable means, here shown 80 to be a strip of fabric 15 anchored at one end to the orifice chamber and at the other to the door. At its other end the door is provided with a hinge pin 16, upon which is mounted a swinging trip arm 17, one end 85 of which is disposed so as to lie in the path of the lateral portion 7^a of the rod 7. Rearwardly beyond the hinge pin 16, the trip arm 17 lies in contact with the face of the closure member, and at its extreme rearward 90 end is bent laterally as at 18.

Overlying the door and the trip arm is a resilient member 19 which may be of any suitable construction, but here shown to be formed of a rubber band anchored at each 95 end to the sides of the orifice chamber and so positioned that it will offer resistance to the movement of both the door and trip arm together or of the trip arm swung separately. Beyond the hinge pin 16 the door 100 14 has a portion bent away from the face of the orifice chamber at right angles to the main body of the door, this portion ending in a second bent portion 20 lying parallel to the main body of the door, the portion 105 20 terminating in an inwardly bent extension 21. The portion 20 is so disposed as to lie in the path of the end 7^a of the rod 7,

the extension 21 serving as a means to prevent the rod 7 sliding off the face of the portion 20 in a manner later to be described.

It will be noted that the head 2 is positioned intermediate the ends of the casing 1 and in such relation that the sound producing and regulating parts just described lie well within the casing and are protected thereby. At its other end the casing is provided with a head 22 shown on dotted lines in Figure 1, this head serving to enclose the bellows and prevent its being injured when the device is in use.

It will be understood that this device is primarily intended for use in talking dolls, more especially dolls of the so-called "ma-ma" type, and ordinarily the device will be so positioned within the body of the doll that upon changes in position of the body of the doll the device will operate so as to give off a sound simulating the human voice.

The operation of the device is as follows: With the doll at rest, let it be assumed that the position of the body of the doll is changed so that the parts of the device take the position indicated in Figure 1.

It will be here seen that the bellows is distended and the weight 6 is at its outer limit of travel. The weight will now have a tendency to move downward under the influence of gravity compressing the bellows and expelling the air therefrom. As the weight moves downward, the expelled air will pass through the aperture 9 into the reed

chamber 10 through the reed 11 into the orifice chamber 12 where it will be compressed by reason of the fact that the door 14 will prevent its escape through orifice 13. The downward movement of the weight, however, carrying with it the rod 7, will cause a portion of the rod 7^a to engage the trip arm 17, and the movement of the rod contacting the trip arm will swing the trip arm and door 14 as a unit on the hinge 15 against the resistance of the resilient member 19. This movement of the rod will thereby cause the orifice 13 to be opened permitting the compressed air to escape so that the reed 11 will give off a clear sound. As the rod

continues its downward movement after having ridden off the trip arm 17, it will at length strike the portion 20 of the door forcing the door to swing on its hinge and to open the orifice 13 a second time, thus producing a second note.

The orifice now continues to be open until the rod 7 has reached the end of its outward travel with the bellows completely collapsed, the stop 21 preventing the rod from riding off the end of the member 20. The second note will be ended by the complete collapse of the bellows.

It will be seen that by the mechanism thus provided, the movement of the doll to a position which causes the weight to collapse the

bellows under the influence of gravity will produce two distinct syllables to be enunciated by the reed, this sound emission producing the "ma-ma" sound. The complete sound emission having taken place, the doll is now moved to a second position where gravity will draw the weight 6 to a position where it will expand the bellows, air being drawn into the bellows through the orifice 13 by leakage. As the weight 6 moves outwardly, the hook portion 7^a will move away from the portion 20 of the door, thus permitting the door to be drawn backwardly into position so as to cover the orifice 13. The hook 7^a, upon clearing member 20, will next engage the outer face of the trip arm 17, causing this trip arm to swing on its hinge 16 against the resistance of the resilient member 19. The member 17, it will be seen, is free to swing inwardly so as to permit the hook to ride off the face thereof and when the hook is clear, it will move to its upper limit of travel, the parts being then in their normal position and ready to begin the cycle of operations.

Upon movement of the doll again to the position where the parts of the sound producing device are as shown in Figure 1, a second series of notes will be given off, it being understood, of course, that the reed construction is such that it will only be caused to vibrate when air passes through it in one direction, in this case upon expulsion of air from the bellows 4.

It will be seen that I have provided a simple and cheaply manufactured device for producing sound in simulation of the human voice, well adapted to attain the purposes and objects previously set forth. While the sound controlling elements are here shown suitably positioned to give the "ma-ma" cry, it will be clear that the relation of these parts may be readily changed so as to produce either a single syllable or a plurality of syllables. Furthermore, by slight modifications, it is possible to change the length of time during which these syllables are emitted. The device has but few moving parts, none of which are easily subject to breakage or likely to get out of order. Furthermore, all the parts may be manufactured of inexpensive material, it being understood that the reed and orifice chambers are ordinarily constructed of pasteboard or like material, while the trip arm and swinging door for the orifice chamber may be made of sheet metal stamped to form and readily bent to the shape indicated.

As many changes could be made in this construction without departing from the scope of the following claims, it is intended that all matter contained in the above description or shown in the accompanying drawing shall be interpreted as illustrative only and not in a limiting sense.

Having thus described my invention, what I claim as new and desire to secure by Letters Patent is:

1. A device of the class described comprising, in combination, a casing, a head mounted therein, sound producing means mounted on said head and means to control the characteristics of the sound emitted, said last named means including an orifice chamber, a swinging door mounted on said chamber to overlie said orifice, a trip arm pivotally mounted on said door, a spring device arranged to elastically hold the inner end of said arm upon the door and the door upon the said orifice, and reciprocating means successively engaging said trip arm and said door whereby to open said orifice during the movement of the said means in one direction, said orifice being closed at all other times.
2. A device of the class described comprising, in combination, a casing, a head mounted therein intermediate the ends thereof, a bellows attached to one face of said head, sound emitting means mounted on the other face of said head in communication with said sound emitting means, a resiliently held swinging door mounted on said last named chamber to overlie said orifice, a trip arm on said door, and means operable upon the collapse of said bellows successively to engage said trip arm and said door whereby to cause successive openings of said orifice during the continuation of such engagements, the said door and the said means being separable and the door being provided with a device constructed to prevent said means from sliding from the door during the opening of the door, said orifice being closed at all other times.
3. A device of the class described comprising, in combination, a casing, a head mounted therein, bellows attached to one face of said head, a reed chamber mounted on the other face of said head in communication with said bellows, an orifice chamber mounted in communication with said reed chamber, a swinging door resiliently held so as to close said orifice, said door having an extending portion, a trip arm swingingly mounted on said door and resiliently held thereagainst, and means operable by the collapse of said bellows successively to open and close said orifice, the said means being arranged to strike and pass said arm effecting a first opening movement of the door, and the door having a device for retaining its engagement with the said means during a second opening of the door.
4. A device of the class described comprising, in combination, a casing, a head mounted intermediate the ends thereof, a bellows mounted on one face of said casing, a reed chamber on the other face of said casing in communication with said bellows, an orifice chamber in communication with said reed

chamber, a door swingingly mounted on said orifice chamber to overlie said orifice, a trip arm swingingly mounted on said door, resilient means to hold said door so as to close said orifice and to hold said trip arm against the face of said door and means operable upon the collapse of said bellows and successively contacting with said trip arm and with said door whereby to open said orifice during such contacts.

5. A device of the class described comprising, in combination, a casing, a head mounted intermediate the ends thereof, a bellows attached to one face of said head, a weight attached to said bellows, a rod attached to said weight and extending through said head, a reed chamber mounted on the other face of said head in communication with said bellows, an orifice chamber in communication with said reed chamber, a door swingingly mounted so as to overlie said orifice, a trip arm pivotally mounted on said door, resilient means to hold said door so as to close said orifice and to hold said trip arm against the face of said door, said door and said trip arm having portions thereof adapted to be engaged by said rod whereby to cause successive disengagements of said door from said orifice upon the collapse of said bellows.

6. A device of the class described comprising, in combination, a casing, a head mounted intermediate the ends thereof, a bellows attached to one face of said head, a weight mounted on said bellows, a rod terminating in a hook mounted on said weight and extending through said head, a reed chamber mounted on said head in communication with said bellows, an orifice chamber mounted on said head in communication with said reed chamber, a door swingingly mounted on said orifice chamber to overlie said orifice and being provided with an extending portion, a trip arm swingingly mounted on said door, resilient means overlying one end of said trip arm and adapted to hold it in engagement with said door and to hold said door so as to close said orifice, said parts being so displaced and arranged that upon the collapse of said bellows said reed will engage successively with said trip arm and the extending portion of said door whereby to cause successive disengagements of said door from said orifice.

7. A sounding device having sound producing means, and means for controlling the same, said last mentioned means including a valve for opening and closing an orifice through which the sound is adapted to issue, and a trip arm pivotally mounted on and supported by said valve and resiliently held in one position with respect thereto and operable to operate said valve.

8. A device of the class described having in combination a bellows, a sound reed car-

ried by one head of the bellows, and operated thereby, a member having an orifice through which the sound from said reed may escape, a pivotally mounted valve for closing said orifice, an arm pivotally mounted on said valve, and resiliently held with respect thereto, and means fixed with respect to the other head of the bellows and adapted to engage said resiliently held arm to operate the valve as the bellows is operated.

9. A device of the class described having in combination a bellows, a sound reed carried by one head of the bellows, and operated thereby, a member having an orifice through which the sound from said reed may escape, a pivotally mounted valve for closing said orifice, an arm pivotally mounted on said valve, and resiliently held with respect thereto, and means fixed with respect to the other head of the bellows and adapted to engage said resiliently held arm to operate the valve as the bellows is operated, and a second arm on said valve also adapted to be directly engaged by said means to operate the valve a second time.

10. A device of the class described having

in combination a casing, a tubular bellows therein, the bellows having one head fixed with respect to the casing, the other head of the bellows being a weighty head adapted to move back and forth by gravity to compress and distend the bellows in the casing, one of said heads having an aperture therethrough, a sound reed carried with said head and adapted to be operated by air forced through said aperture by the bellows, a member having an orifice through which the sound from said reed is adapted to escape, a pivoted valve for said orifice, a rod fixed with respect to the opposite head of the bellows and extending through the bellows and slidably through the other head of the bellows on which the reed is located, said rod and valve having cooperating means whereby the rod operates the valve, one having two projections adapted to be directly engaged by the other successively, one of said two projections being pivotally mounted with respect to the other.

In testimony whereof, I affix my signature.

FRED EVANS.
